(57) **CLAIM**

The ornamental design for a motor vehicle as shown and described.

DESCRIPTION

FIG. 1 is a top, front and left side perspective view of a motor vehicle showing our new design;

FIG. 2 is a top and front side perspective view thereof;

FIG. 3 is a top, front and right side perspective view thereof;

FIG. 4 is a front view thereof;

FIG. 5 is a left side view thereof;

FIG. 6 is a top view thereof;

FIG. 7 is an elevational view of the profile of the claim, taken along line 7-7 in FIG. 5;

FIG. 8 is an elevational view of the profile of the claim, taken along line 8-8 in FIGS. 5; and,

FIG. 9 is an elevational view of the profile of the claim, taken along line 9-9 in FIG. 5.

The broken lines in FIGS. 1-6 surround portions of the claimed design and form no part of the claimed design. The broken lines in FIGS. 7-9 show inner portions of the motor vehicle profile that form no part of the claimed design.

1 Claim, 7 Drawing Sheets
